ELECTROMECHANICAL TELEPHONE SWITCHING SYSTEM

Filed May 23, 1924

UNITED STATES PATENT OFFICE.

FRITZ ALDENDORFF, OF BERLIN-WILMERSDORF, GERMANY; CHARLOTTE ALDEN-DORFF HEIRESS OF SAID FRITZ ALDENDORFF, DECEASED.

ELECTROMECHANICAL TELEPHONE SWITCHING SYSTEM.

Application filed May 23, 1924, Serial No. 715,433, and in Great Britain June 11, 1923.

This invention relates to electromechanical telephone switching systems and its object is to provide an efficient and yet simple line-finder, or revertively acting trunk-finder 5 starting-arrangement by which a calling party is enabled to send in his impulses upon the response of his line relay and, as a rule, without waiting until a finder brush has travelled up to a bank contact connected to or 10 associated with his line. This object is accomplished by providing for a group of subscribers or trunk lines, which are multipled to the bank contacts of a set of finders, a transitorily engaged dialling trunk adapted 15 to be automatically connected after each use by a trunk finder to a free trunk and to be connected to a calling line by a relay associated therewith the moment the line is placed in a calling condition. A trunk finder is pro- 20 vided whose hunting action is started by an impulse sent from a line finder whose hunting operation is initiated by the aid of a circuit that extends through a calling trunk or subscriber's line. The stopping or test relay 25 circuit of the line finder is directly controlled by a contact of the release relay of the numerical switch associated with the line finder. To relieve the relay individual to each subscriber's line or calling trunk line of the 30 necessity of moving a large number of contacts when only energized by a current that has to flow over a subscriber's line, a common relay may be provided by which a local circuit through a winding of the subscriber's 35 line relay is closed so as to cause this relay to move a heavily loaded armature that moves a considerable number of contacts.

The invention is shown in the drawing in which

40 Fig. 1 shows an arrangement in which each line is provided with a relay equipped with a slowly retracting armature.

In Fig. 2 a modified arrangement is shown in which there is only one slow-acting relay 45 for a whole group of subscribers.

In Fig. 1 a subscriber's station 1 is shown connected by a line 2, 3 to a set of bank contacts in a group of finders of which one line finder LF is shown. The subscriber's line is 50 also connected through the contacts of a cut-off relay 5 to a line relay 4 which, when it attracts its armature (diagrammatically illustrated in the drawing) connects the subscriber's station to a dialling trunk 7 connected to 55 a trunk finder TF. The trunk finder TF is

arranged to preselect a free trunk such as 20, 21, that forms a connecting link between a line finder LF and a numerical switch NS or the like, which may be a group selector or a connector.

60

As this invention only relates to the line finder part of the exchange the following detailed description of the circuits will be limited chiefly thereto. When the subscriber 1 calls by raising his receiver, a current flows 65 from the positive pole of the battery through contact 25 of a relay 6 common to a group of subscriber's wires 26, which is multipled to the contacts of all the relays like 4 and 5 associated with the various lines, contact 27 70 of the cut-off relay 5, wire 2, subscriber's station 1, wire 3, contact 28, line relay 4, contact 29, contact 30 of common relay 6 to the negative pole. The line relay 4 is energized and opens its contact 31 so as to render the 75 calling line engaged at the contact banks of the connectors (not shown). The line relay 4 also opens its contact 29, after previously closing its contact 32 so as to maintain itself energized. It also closes its contacts 33, 34 80 and 35. By contact 33 it connects the cut-off relay 5 to the bank contacts like 36, in the banks of the finders, like LF. By the contact 34 a circuit is closed through the common relay 6 which opens its contacts 30 and 25 and 85 thus for a brief interval prevents any other line relay like 4 in the same group of subscribers from being energized by another calling line in the same group being placed in the calling condition. The positive pole of 90 the battery, which is disconnected at the contact 25 from the wire 26, is reconnected to this wire by the contact 35 through the transitorily engaged dialling trunk 7, which will be connected at this moment, as hereinafter 95 described, to the impulse relay 19 of a free trunk 20, 21. Hence current will now flow through the line relay 4 of the calling subscriber over the following path: from the positive pole through the winding of the im- 100 pulse relay 19, wire 36, wiper 8, contact 37 of the relay 12, dialling trunk 7, contact 35, contact 27, wire 2, station 1, wire 3, contact 28, line relay 4, contact 32 to the negative pole. The subscriber may therefore com- 105 mence sending in numerical impulses im- mediately after raising his receiver without waiting for his line to be connected through to a free trunk by the hunting wipers of any kind of selector switch. When the impulse 110

relay 19 is energized, a circuit is closed through the release relay 38, this circuit extending from the minus pole through contact 40, release relay 38, resistance 41 to the positive pole. The release relay closes its contacts 42, 43 and opens its contact 44. By contact 43 an energizing circuit for the driving magnet 17 of the line finder LF is closed which extends from the negative pole through 43, contact 45 of the test relay 47, driving magnet 17, impulse producer IP to the positive pole. The impulse producer IP has a winding of a very high resistance and attracts its armature 48 which short circuits the high resistance winding so as to enable a current to flow through the driving magnet 17 strong enough to energize it. The impulse producer then allows its armature to drop back, due to the short circuit through the contact 48, and the high resistance thus reinserted in the circuit of the magnet 17 causes the armature of the latter to drop back. The impulse producer then again attracts its armature and short circuits its high resistance to reenergize the magnet 17. This sequence of events is repeated until the wiper 15 of the line finder LF strikes the bank contact 36, when the test relay or stopping relay 47 is energized by a current which flows from the negative pole through 43, 47, 15, 36, 33, cut-off relay 5 to the positive pole. The stopping relay 47 closes its contacts 48, 49, 50 and 46 and opens the circuit of the driving magnet 17 at contact 45. The calling subscriber's line relay 4 is now cut off from the line by the opened contact 28, and the dialling trunk 7 is cut off by the opened contact 27.

The calling subscriber's dialling impulses, which may have been proceeding over the dialling trunk 7 to the impulse relay 19, will now proceed through the wipers 13, 14 of the line finder LF through the following circuit: positive pole of the battery, left hand winding of 19, trunk wire 20, 48, 13, bank contact 51, 2, station 1, 3, bank contact 52, 14, 49, 21, right hand winding of the impulse relay 19 to the negative pole. When the armatures of the impulse relay 19 oscillate in response to the dialling impulses, a series of switch setting impulses is sent, first through the group selecting magnet 22 or tens magnet and then, after the change-over, to the individual line selecting magnet or units magnet 23 of the numerical switch NS, which may be a switch of the kind described with reference to Fig. 2 of my British Patent No. 196,990.

The moment the wipers 13, 14, 15, 16 of the line finder are set onto the calling line, and the stopping relay 47 is energized, the trunk finder TF is started to hunt for another free trunk. This starting operation is effected by the closure of a contact 46 by which a circuit is completed through 55, bank

contact 56' of the finder TF, wiper 9, left hand winding of relay 12 to the negative pole. The relay 12 opens its contact 37 and closes its contacts 57 and 58. The contact 58 applies the impulse producer IP, which is connected to the terminal T', to the driving magnet 11 of a trunk finder and this magnet then continues receiving impulses until the relay 12 is deenergized. The energization of the relay 12 continues as long as the wiper 10 strikes bank contacts connected to wires like 60 that lead to engaged trunks; for the release relays 38 of engaged trunks will all be energized and will thus connect the positive pole through a contact like 61 to their wires 60, and the right hand winding of the relay 12 will thus be kept energized by currents flowing from the positive pole to contacts like 61 and wires like 60, wiper 10 and contact 57. During the travel of the wiper 10 from one bank contact to another the relay 12 is maintained energized by the left hand winding receiving impulses from the positive pole, impulse producer, contact 58 and the wire 65. The moment the wiper 10 reaches a wire like 60 leading to a disengaged trunk, the right hand winding of the relay 12 is deprived of current, and as the left hand winding of the relay will also be currentless at this moment the relay 12 will allow its armature to drop back so that the circuit of the magnet 11 is opened at 58 and the dialling trunk 7 is connected through the contact 37 and the wiper 8 to a wire like 36 leading to the impulse relay like 19 of a disengaged trunk like 20, 21. The dialling trunk 7 will then be ready to conduct dialling impulses from another calling line to another free trunk.

In Fig. 2 the relays associated with the calling lines are modified, but all the other parts of the dialling trunk and finder starting arrangement are precisely similar to the arrangements in Fig. 1. The line relays 104^A in Fig. 2 are provided with two armatures, an easily moved armature which operates the contacts 134, 136, and a heavier armature which operates the contacts 131, 133, 135, 137, 138. The common relay 106, which allows its armatures 125, 126' to retract slowly, is first energized in parallel with the line winding 104 of a line relay, and then the left hand winding 104' of the line relay is energized in a local circuit closed by the common relay 106. The line relay 104^A connects the wire 102 through its contact 135 to the dialling trunk 7 which is arranged exactly like the similarly designated dialling trunk in Fig. 1.

When the subscriber 101 calls, the line relay is energized by a current which flows from the positive pole through 125, wire 126, contact 137, winding 104, contact 128, wire 103, station 101, wire 102, contact 127, contact 138 to the negative pole. The line relay, by its easily moved armatures, closes its contacts 130

134, 136 and the common relay 106 is then energized in parallel with a winding 104. The relay 106 then closes a local circuit to the winding 104' which extends from the positive 5 pole through 126', 136, 104' to the negative pole. The heavier armature of the line relay is then attracted so that the contacts 133, 131, 137, 135, 138 of the line relay are operated. By the opening of the contact 125 10 of the common relay 106 the energization of other line relays is prevented until the dialing trunk 7 is released for another call as explained in connection with Fig. 1.

The line relays in Fig. 1 are provided with 15 a coil 200 connected to a tone producer (not shown) which gives rise to a tone in the receiver of a calling station in case the line relay 4 is not immediately energized when the call is made. In Fig. 2 a similar tone producer coil 200' is provided in connection 20 with the common relay 106. In this case the tone is only heard at the calling station when the line relay of the same is energized.

I claim:—

25 1. In a telephone exchange system, a plurality of line finders having bank contacts and cooperating wipers, a group of lines multiplied to said bank contacts, link circuits terminating in said wipers, a numerical switch 30 associated with each link circuit, impulse responsive means associated with each numerical switch, a dialling trunk, a relay having armatures responsive to different degrees of magnetization of said relay for connecting a 35 calling line through said trunk with the impulse responsive means of a numerical switch, means for actuating said relay upon the initiation of a call, and means for starting a line finder associated with the last-mentioned switch to hunt for the calling line in 40 response to the operation of said impulse receiving means.

2. In a telephone system, a plurality of 45 lines, line finders, a plurality of lines connected to the contact banks of said finders, a line relay for each line for establishing the calling condition of the same in said contact banks, contacts for said relay responsive to a small magnetization of its magnetic core to 50 close an immediate dialing circuit therethrough, and other contacts for said relay responsive to a great magnetization of said core.

3. In a telephone system, telephone lines, numerical switches common to said lines, a 55 plurality of trunks leading from said lines to said switches, means for preselecting an idle one of said trunks, means for enabling a calling subscriber to dial immediately into said preselected trunk comprising a relay individual to each of said lines, said relay having an armature responsive to one degree of magnetization for completing a dialing circuit from the associated telephone line to the preselected trunk, and another circuit controlling armature responsive to a different degree of magnetization only. 60

4. In a telephone system, telephone lines, a numerical switch common to said lines, a 70 plurality of trunks leading from said lines to said switch, means for preselecting an idle one of said trunks, a line finder responsive to the initiation of a call on one of said lines for causing said line to be automatically associated with said preselected trunk, a line relay associated with said line for controlling the action of said line finder, said relay having an armature responsive to one degree of magnetization adapted to close an immediate dialing circuit to said preselected trunk while 80 said line finder is seeking said line, and another circuit controlling armature responsive to a different degree of magnetization only. 75

5. In a telephone system, the combination 85 of a telephone line, a numerical switch, a plurality of trunks leading from said line to said switch, means for preselecting an idle trunk, a marginal line relay associated with said line, said relay having an armature thereon 90 immediately responsive to the initiation of a call on said line for closing a dialing circuit from said line to said preselected trunk. 90

6. In a telephone system the combination 95 of a telephone line, a plurality of trunks common to said line, line finder switches for connecting said trunks to said line, means comprising said line, one of said trunks and one of said switches for completing a dialing circuit, a marginal line relay for said line, and 100 means comprising contacts of said line relay for completing a dialing circuit therethrough in shunt to a portion of the first mentioned dialing circuit.

In testimony whereof I affix my signature.
FRITZ ALDENDORFF.
